UNITED STATES PATENT OFFICE

FONT R. MCGEE, OF ROCHESTER, NEW YORK, ASSIGNOR, BY MESNE ASSIGNMENTS, TO
SCHELTER LAST COMPANY, OF ROCHESTER, NEW YORK

COMBINED SHANK STIFFENER AND ARCH SUPPORT

Application filed January 21, 1928. Serial No. 248,535.

The present invention relates to shoes and a method of making the same, an object of the invention being to provide a shoe with a novel support incorporated therein for the metatarsal arch.

To these and other ends, the invention consists of certain parts and combinations of parts, all of which will be hereinafter described: the novel features being pointed out 10 in the appended claim.

In the drawings:

Fig. 1 is an underside view of a last used in the present method;

Fig. 2 is a transverse section through the 15 last;

Fig. 3 is an underside view of the shoe after it has been lasted and before the arch support and the outer sole are attached;

Fig. 4 is a similar view showing the arch 20 support in position;

Fig. 5 is a vertical section through the shoe after the insole and heel have been attached;

Figs. 6 and 7 are respectively opposite sides of the arch support; and

Fig. 8 is an edge view of the arch support.

In carrying out the illustrated embodiment of the invention, there is provided a last 1 the under side of which between the toe portion 1 and the heel portion 2 is formed with a 30 longitudinally extending depression 3 curved in cross section and extending from a point 4 immediately in rear of that portion which is to form the portion of the shoe beneath the toe joints.

The insole 5 of any style is tacked to the last 35 in the usual manner preferably after being moistened or tempered so that it has flexibility and a roller or other device is then pressed against the insole 5 to force the insole into

40 the depression 3 of the last so that the outer face of the insole at the shank portion becomes depressed at 5^a in the main arch of the shoe extending to a point slightly behind the joints of the metatarsal arch. After the insole 45 has dried, the upper 6 is lasted by any suitable process, that shown being the ordinary Good-year process.

After the lasting, the usual trimming may 50 take place and the bottom of the shoe will appear as shown in Fig. 3. The depression 5^a

in the insole of the shoe is now filled by an arch support 7 preferably in the form of a piece of leather having a flat side 7^a and a convex side 7^b the support conforming to the depression 5^a in the insole 5. This arch support 7 in this instance is secured by a rivet 8 to the forward end of a shank stiffener which, in this instance, comprises an upper plate 9 and a lower reinforcing plate 10, the latter having a strengthening rib 11 on its 55 under side and being spot welded at 12 to the upper plate 9 so that the upper plate projects beyond both ends thereof, the rivet 8 passing through the forward end of the arch support and tacks or fasteners 13 being 60 driven through perforations 14 at the other or rear end of said plate 9. The shoe may then be filled in the usual manner, the outer sole 15 secured to the welt, and the heel 16 attached.

While the invention is shown as embodied in what is known as a Goodyear welt shoe it is apparent that the shoe is not limited to shoes made according to the Goodyear process. This invention provides a raised portion 70 on the inner face of the insole conforming to the shape of the foot at the forward end of the main arch and extending substantially to that portion of the metatarsal arch immediately back of the toe joints. In this 75 way the toe joints are left free to function and the metatarsal arch is supported so as to maintain the arched condition.

The support acts merely upon the cords of the three intermediate metatarsal arch bones 85 without reaching any of the joints of the arch or the joint at the instep. The cords of the first and fifth metatarsal bones are not acted upon or supported by the support. This causes the metatarsal arch to assume its correct arched position because the cords are 90 caused to function naturally.

What I claim as my invention and desire 95 to secure by Letters Patent is:

A shoe having its inner sole pressed upwardly in the form of a projection, the front edge of the projection being in rear of the metatarsal arch and the sides being spaced from the side edges of the inner face of the inner sole at opposite sides so that the pro- 100

jection pushes upwardly only on the cords leading to the three intermediate joints of the metatarsal arch while permitting the two outer cords leading to the arch to function without upward pressure by the projection, and means for rigidly supporting said pressed up portion in the shoe, said means comprising a long narrow shank of uniform width arranged between the inner and the outer soles, and having its rear end secured at the heel portion of the shoe, a lower reinforcing plate secured to the shank and extending longitudinally thereof and provided at its lower face with a longitudinal rib located at the central portion of the reinforcing plate and a rigid projection arranged on the upper face of the shank on the arched portion thereof projecting beyond the forward end and side of the shank and lying in and conforming to the pressed up portion of the inner sole.
